FLUID PUMP OR MOTOR

Eugene F. Prondecki, Turner Falls, Mass.

Application September 21, 1954, Serial No. 457,440

1 Claim. (Cl. 103—125)

This invention relates to improvements in apparatus adapted for use as a pump or motor.

The principal object of the invention is the provision of apparatus which is constructed and arranged for operation as a fluid pump or motor.

The apparatus is characterized by a pair of cylindrical members which are rotatable on parallel axes one of said members being provided with a continuous rib extending from the periphery thereof and helically and longitudinally thereof in circumferentially spaced runs and the other having a peripheral groove operatively receiving said rib in relative rotation of the members.

All of the above cited objects I accomplish by means of such structure and relative arrangement of parts thereof, as will fully appear by a perusal of the description below and by various specific features which will be hereinafter set forth. To these above and other ends and with the foregoing and various other and ancillary features and advantages and objects of my invention as will become more readily apparent as the description proceeds, my invention consists in certain novel features of construction, in a mode of operation, and in the combination organization and arrangement of parts as will be hereinafter more particularly pointed out in the claim hereunto annexed and more fully described and referred to in conjunction with the accompanying drawings wherein:

Fig. 1 is a front elevational view of apparatus embodying the novel features of the invention and;

Figs. 2 and 3 are plan views of the primary and secondary cylinders of the apparatus shown in Fig. 1.

In the accompanying drawing, I have illustrated a complete example of a physical embodiment of the invention in which the parts are combined and arranged in accordance with one mode which I have devised for the practical application of the principles of the invention.

It will however, be understood that changes and alterations are contemplated and may be made in these exemplifying drawings and mechanical structures, within the scope of the claim, without departing from the principles of the invention.

Referring to the drawings more in detail the invention will be fully described.

A housing is shown at 2 which has upper and lower bores 4 and 6 for cylinders. Said bores are disposed on parallel axes and adjacent sides intersect, as shown.

End walls such as 8, as shown, in Fig. 1, are provided which are secured to forward and rear faces of the housing 2 so as to close opposite ends of the bores 4 and 6. The walls may be secured to the housing by screws such as 10 which extend through the walls 8 into tapped holes 12 of the housing.

A primary cylinder 14 is rotatable in the bore 4 and

2

a secondary cylinder 16 in the bore 6 has a shaft 18 which is rotatable in bearings such as 20 of the end walls 8.

The cylinder 16 has on its periphery a continuous vane 5 or rib 22 arranged in a plurality of runs 24. The runs project radially outwardly. These runs 24 are arranged in spaced relation circumferentially of the cylinder and extend helically and longitudinally of said cylinder.

The cylinder 14 is provided with a substantially continuous groove 26 which is arranged, as shown, with a pair of runs which extend from end to end of the cylinder and helically thereof. Opposite ends of the groove runs intersect or connect at 26', as shown in Fig. 2.

The cylinder 14 is fitted in the bore 4 for free rotation therein without undesired looseness and likewise the outer side of the rib 22 of the cylinder 16 is fitted in the bore 6 for rotation without appreciable looseness.

The rib and groove of the cylinders are arranged for meshing engagement so that the cylinders are simultaneously rotatable.

Elongated channels 30 and 32 at opposite sides of a vertical plane extending through the axes of rotation of the cylinders open into the bore 6. Opposite ends of the channels are closed by the end walls 8. Passageways 34 and 36 extend from the channels 30 and 32 and connections 38 and 40 are provided for connecting the apparatus in a fluid system.

When the apparatus is used as a pump with cylinder 16 rotated counterclockwise from a source of power, such 30 as a motor or the like, connection 38 will be considered as the inlet. The runs 24 of the rib propel fluid counterclockwise to channel 32 and connection 40 which will be the outlet.

The runs of the rib and of the groove in the cylinders 35 intermesh in such a way as to prevent leakage therewith. The cylinder 14 acts as a buffer so that fluid is carried around to channel 32.

When the apparatus is used as a motor, fluid under pressure entering connection 38, as an inlet, acts on the runs 24 of the rib 22 of the cylinder 16 to rotate said cylinder counterclockwise. Power may then be taken from the shaft 18 of said cylinder.

The invention may be embodied in other specific forms without departing from the essential characteristics thereof. Hence, the present embodiments are therefore to be considered in all respects merely as being illustrative and not as being restrictive, the scope of the invention being indicated by the appended claim rather than by the foregoing description and all modifications and variations as fall within the meaning and purview and range of equivalency of the appended claim are therefore intended to be embraced therein.

What it is desired to claim and secure by Letters Patent of the United States is:

Apparatus of the class described comprising in combination, a housing provided with elongated parallel primary and secondary bores having adjacent intersecting sides providing a connecting slot therebetween, end plates secured to the housing closing opposite ends of said bores, a primary cylinder journaled in the wall of the primary bore, a secondary cylinder in the secondary bore having shafts at its opposite ends journaled in said end plates, said housing provided with elongated channels in communication with and along the secondary bore at opposite sides of said slot and inlet and outlet passageways 55 in communication with said channels, said secondary cylinder provided with circumferentially spaced outward-

ly extending ribs, adjacent ribs relatively diverging from one to the other end of the cylinder, adjacent ends of adjacent ribs at opposite ends of the cylinder being interconnected whereby said ribs form a continuous rib extending back and forth between the ends of the cylinder and therearound and the periphery of the primary cylinder provided with circumferentially spaced grooves extending from end to end thereof, adjacent grooves relatively converging from one to the other end of said primary cylinder and arranged to receive the rib of the secondary cylinder for simultaneous relative rotation of said cylinders.
